(57) CLAIM

The ornamental design for a shopping cart corral having an entry portion to which advertisements are affixed, as shown and described.

DESCRIPTION

FIG. 1 is a perspective view of a shopping cart corral having an entry portion to which advertisements may be affixed;

FIG. 2 is a side view thereof;

FIG. 3 is a front view thereof;

FIG. 4 is a rear view thereof;

FIG. 5 is a top view thereof;

FIG. 6 is a perspective view of a shopping cart corral having an entry portion to which advertisements may be affixed;

FIG. 7 is a side view thereof;

FIG. 8 is a front view thereof;

FIG. 9 is a rear view thereof; and,

FIG. 10 is a top view thereof.

The broken line showings of the shopping cart corral in FIGS. 1–10 are for the purpose of illustrating an environment only and form no part of the claimed design.
